UNITED STATES PATENT OFFICE

FAUSTA VITTORIA MENGARINI, OF NEW YORK, N. Y.

DESIGN FOR A STATUE OR ARTICLE OF ANALOGOUS NATURE

Application filed December 28, 1931. Serial No. 42,259. Term of patent 3½ years.

● To all whom it may concern:

Be it known that I, FAUSTA VITTORIA MEN-GARINI, a subject of the King of Italy, and a resident of New York, borough of Manhattan, in the county of New York and State of New York, have invented the new, original,
and ornamental Design for a Statue or Article of Analogous Nature, of which the following is a specification.

Reference is had to the accompanying drawings, forming part thereof, wherein—

Figure 1 is a front perspective view of a statue or article of analogous nature.

Figure 2 is a side perspective view of the statue or article of analogous nature shown

statue or article of analogous nature shown
in Figure 1.

I claim:

The ornamental design for a statue or article of analogous nature substantially as shown.

FAUSTA VITTORIA MENGARINI.
